UNITED STATES PATENT OFFICE.

JOSÉ S. CANDRAY, OF SAN FRANCISCO, CALIFORNIA.

LIGHTER-THAN-AIR CRAFT.

Application filed September 30, 1926. Serial No. 138,686.

The present invention relates generally to a lighter than air craft and more particularly to a structure which uses a central stator core and an outer rotor covering on which is mounted a spiral propelling fin and the prime object of the invention lies in the provision of a device of this nature which is extremely strong and durable, capable of great speed, easy to maneuver, efficient and reliable.

Another very important object of the invention lies in the provision of a structure of this nature wherein lighter than air gas containers are disposed about the core and the rotor casing revolved thereabout.

Another very important feature of the invention lies in the provision of a spiral propelling fin about the rotor which is formed in sections that may be moved to an ineffective position for assisting in different maneuvers.

Another very important object of the invention lies in the provision of an induction motor built in the sections so as to obtain the maximum efficiency.

With the above and numerous other objects in view as will appear as the description proceeds, the invention resides in certain novel features of construction, and in the combination and arrangement of parts as will be hereinafter more fully described and claimed.

In the drawings:

Figure 1 is an elevation of the lighter than air craft embodying the features of my invention,

Fig. 2 is a fragmentary longitudinal vertical section through the craft,

Fig. 3 is a longitudinal detail section through the core,

Fig. 4 is an enlarged detail section through a portion of the craft,

Fig. 5 is a transverse section through the core,

Fig. 6 is a fragmentary transverse section through the craft taken at one point,

Fig. 7 is a similar view taken at another point,

Fig. 8 is a detail fragmentary perspective view of a portion of the rotor showing par-

ticularly the construction of the propeller fin,

Fig. 9 is an enlarged fragmentary detail transverse section through the craft showing particularly the motor construction,

55

Fig. 10 is a detail view of the induction coil used in the motor construction.

Referring to the drawings in detail, it will be seen that the numeral 5 denotes the core which is of an elongated tubular construction terminating at its forward end in a bullet-shaped tip 6 in which the observer will be situated. A suitable entrance 7 may be provided in the tip for allowing ingress and egress of passengers particularly when the

60

air craft is anchored at the nose as is a somewhat common practice today. The rear end of the core has an enlargement 8 in the form of a casing which gradually tapers to the point. This casing 8 forms the tail of

70

the craft. In the axis portion of the tail casing 8 there is preferably located the control room 9 which will be in telephonic communication with the observation tip 6. In the bottom compartment 10 of the tail cas- 75

ing 8 there is located the prime mover 11, the preferred entrance to the craft will be at 12, that is, at the bottom of the tail casing 8 and a suitable ladder, elevator, or any other preferred means 14 may be utilized for

80

allowing the passengers, freight, and the like to get to the core 5 of the craft. The relatively large compartment 15 of the tail casing 8 is adapted to receive a large lighter than air gas container 16. On the exterior

85

of this tail casing 8 there are provided vertical and horizontal fins 17 extending longitudinally and having at their rear ends rudders and elevators 18. These are the usual

90

controlling features of all air craft of this nature and of course may be varied ex-

tensively.

Particular attention is now directed to stress distributing features used with the core 5. This core is braced similar to the

95

bracing used in bridges having alternately arranged exterior arch braces 19 and interior arch braces 20 of suitable trestle work or the like. This form of bracing provides a very strong and rigid inner core 5 which

100

is absolutely necessary in an air craft such as I contemplate. Particular attention is directed to Fig. 3 wherein I have shown the utilization of the space between the braces 5 20 as compartments, rooms, or the like. In this figure the room shown is indicated by the numeral 21 and has suitable seats 22 mounted therein and baggage racks 23 suspended from the ceiling of the room. Suitable 10 lighting facilities 24 may be provided. An important feature will be the utilization of piping 25 running throughout the core in order that fresh air may be delivered to the rooms, the outlet nozzles being shown at 26 15 well distributed. The racks 23 may be used as sleeping bunks. The distribution of the air in the room 21 is shown to advantage in Fig. 5, it being noted that the outlet nozzles 26 are adjacent both the floor and the ceiling. The room 21 is provided with a doorway 27 at each end so that it is possible to walk through the core from one room to the other.

Between the exterior braces 19 there are 25 disposed about the core annuli 28 which are braced as indicated at 29 within the core. A large substantially cylindrical-shaped rotor casing 30 is disposed about the core 5 and the forward end thereof is tapered to 30 the tip 6 to form the nose of the craft. This rotor casing is provided at intervals with wheel-like trestle work 31 rotatable about the annuli 28, suitable anti-friction bearings 32 being interposed between the wheel-like 35 trestle work 31 and the annuli 28. In two or more places throughout the length of the casing 30 the wheel-like trestle work 31 is duplicated as is indicated at 31', and of course, the annuli will be duplicated in accordance therewith as at 28'. The trestle-work 40 31' and annuli 28' are spaced and a wheel-like trestle-work 34 is disposed about the core between the trestle-work 31'. The casing 30 is provided with a trestle-work structure 35 disposed about the wheel-like trestle-work 34. The adjacent edges of the trestle-works 34 and 35 are provided with coils 36 of suitable formation for providing an induction motor which will cause the rotation of the rotor casing about the core 5. It is preferable, as is shown to advantage in Fig. 2, that one of these induction motors be located adjacent the nose of the craft and the other adjacent the tail casing 8. It 55 is quite apparent, however, that these induction motors may be duplicated throughout the length of the craft as often as may be necessary. This will depend, as is quite apparent, on the length of the air craft and the speed desired and other features.

The spaces in the rotor casing 30 defined by the trestle-work 31 and 31' are utilized for receiving lighter than air gas containers 38 which will be anchored to the core in any suitable manner. By referring to Figures 5

and 6 it will be seen that the exterior braces 19 are arranged at 90° intervals and there will be a gas container between each pair of these braces and also auxiliary gas containers 39 between the larger gas containers 38. 70 I have not shown the anchoring means for these containers as this may be in the nature of any suitable structure such as is commonly used at the present time for that purpose. The positioning of the prime mover 11 in the bottom of the tail casing 8 is for the purpose of placing the center of gravity of the craft well below the axis thereof so that the core will remain stationary while the casing rotates. I consider this feature of stabilization more a matter of engineering than invention, and have not therefore, gone into details concerning the same as various different ways are obvious without departing from the principle of this invention as will be claimed hereinafter. I contemplate in using duralumin throughout this air craft in the formation of the covering of the rotor casing 30 and also in the trestle-work structure in 90 order that the craft may be as light as possible. This material, however, does not enter into the essence of the invention as other materials now known and others which may become known may be well used in an 95 air craft embodying the real features of my invention. The nose of the rotor casing is braced by diagonal trestle-work 40 as is indicated to advantage in Fig. 2. I have not shown the gas containers in the nose, but 100 of course they may be used if desired.

The letter F denotes generally a spiral propeller fin which is disposed about the rotor casing 30 throughout its entire length as is clearly shown in Fig. 1 of the drawing. 105 This spiral propeller fin F forms a screw when the rotor casing is in motion about the axis core and enables the air craft to attain a great speed both in relatively dense air and rarefied air as is found in the upper strata. 110 At times it will be found that the entire length of this fin F is not necessary and I therefore form the fin in a plurality of sections 41 as is indicated to advantage in Fig. 8. These sections 41 have posts 42 disposed between them, said posts being properly braced as at 43. The sections are hingedly mounted on the casing 30 as is indicated at 44. Each section 41 or a suitable number of said sections 41 are provided with arcuate racks 45 and electric motors 46 are mounted on the casing and their shafts are provided with pinions 47 meshing with the arcuate racks 45. It is obvious that these motors 46 may be controlled from the control room 9 so that the desired sections 41 may be folded down, that is, swung to be disposed somewhat flat on the casing 30 thereby being intersected. The sectional formation of the propeller fin F is very im-

portant in that it provides a great flexibility in the control of the craft as will be quite apparent. Thus the speed of the craft may be increased or decreased by the mere manipulation of the sections 41 through their 5 motors 46. The posts 42 are very important since when the sections 41 are in their upright positions they are braced by these posts 42 thereby taking the strain off the hinge 10 connections 44.

The propelling means just described in detail above has the advantage of lending additional power for lift and fly and also for reducing to a minimum the resistance of the 15 air. This construction eliminates to a considerable extent all head resistance owing to the screw-nature of the propulsion.

From the foregoing, it will be readily apparent that I have provided an efficient and 20 substantial device of the character described and while this specification manifests in detail the preferred construction of the invention, I do not wish to be understood as limiting myself to the specific details of construction 25 and arrangement of parts as herein described and illustrated, as it is manifest that variations and modifications may be resorted to in the features of construction and arrangement of parts in the adaptation of the 30 device to various conditions of use without departing from the spirit and scope of the invention. I therefore reserve the right to 35 all such variations and modifications as properly fall within the scope of my invention and the terms of the appended claims.

From the foregoing, it is thought that the construction of my invention will be clearly understood and, therefore, a more extended explanation has been omitted.

Having thus described my invention, what I claim as new is:

1. An air craft of the class described including, in combination, a stator core, a rotor casing about the core, means for rotatably mounting the casing about the core, lighter than air lift means mounted about the core and in the casing, means for rotating the casing, and propelling means on the casing.

2. An air ship of the class described including, in combination, a stator core having the rear end thereof enlarged to form a tail casing, a rotor casing about the core, means for rotatably mounting the rotor casing about the core, lighter than air lift means mounted about the core and in the rotor casing, further lighter than air lift means mounted in the tail casing, means for rotating the rotor casing, and propelling means on the rotor casing.

3. An air craft of the class described including, in combination, a stator core, a rotor casing about the core, means for rotatably mounting the casing about the core, lighter than air lift means mounted about

the core and in the casing, means for rotating the casing, and a spiral propeller fin on the exterior of the casing.

4. An air craft of the class described, including, in combination, a stator core having a rear enlargement forming a tail casing, a rotor casing about the core, means for rotatably mounting the rotor casing about the core, lighter than air lift means mounted about the core and in the rotor casing, other lighter than air lift means mounted in the tail casing, for rotating the rotor casing about the core, and a spiral propelling fin disposed about the rotor casing.

5. An air craft of the class described including, in combination, a stator core, a rotor casing about the core, means for rotatably mounting the casing about the core, lighter than air lift means mounted about the core and in the casing, means for rotating the casing, and a spiral propelling fin disposed about the casing and formed in sections and means for swingably mounting the sections and controlling them to an upright or down position.

6. An air craft of the class described including, in combination, a stator core, a tail casing formed on the rear end of the stator core, a rotor casing disposed about the core, means for rotatably mounting the rotor casing about the core, lighter than air lift means mounted about the core and the rotor casing, lighter than air lift means mounted in the tail casing, means for rotating the rotor casing, a spiral propelling fin disposed about the rotor casing throughout its length, said fin being formed in sections, means for hinging the sections to the rotor casing, and means for swinging the sections to upright or down position.

7. An air craft of the class described including, in combination, a stator core, a tail casing formed on the rear end of the stator core, a rotor casing disposed about the core, means for rotatably mounting the rotor casing about the core, lighter than air lift means mounted about the core and the rotor casing, lighter than air lift means mounted in the tail casing, means for rotating the rotor casing, a spiral propelling fin disposed about the rotor casing throughout its length, said fin being formed in sections, means for hinging the sections to the rotor casing, and means for swinging the sections to upright or down position, elevating and steering means on the tail casing.

8. An air craft of the class described including, in combination, a stator core, a tail casing formed on the rear end of the stator core, a rotor casing disposed about the core, means for rotatably mounting the rotor casing about the core, lighter than air lift means mounted about the core and the rotor casing, lighter than air lift means mounted in the tail casing, means for rotating the rotor cas-

ing, a spiral propelling fin disposed about the rotor casing throughout its length, said fin being formed in sections, means for hinging the sections to the rotor casing, and 5 means for swinging the sections to upright or down position, elevating and steering means on the tail casing, said core being braced throughout its length by arched exterior stress distributing elements alternately arranged with interior arch stress distributing elements.

9. An air craft of the class described including, in combination, a stator casing, a rotor casing about the core, means for rotatably mounting the casing about the core, lighter than air lift means mounted about the core and in the casing, propelling means on the casing, and a built-in induction motor between the stator core and the rotor casing,

20 10. An air craft of the class described including, in combination, a stator casing, a rotor casing about the core, means for rotatably mounting the casing about the core, lighter than air lift means mounted about the core and in the casing, propelling means on the casing, and a built-in induction motor between the stator core and the rotor casing, said propelling means being in the form of a spiral propelling fin disposed on the exterior 25 of the casing and formed in sections, means for hinging the sections to the casing, and means for swinging the sections to upright or down position.

11. An air craft of the class described including, in combination, a stator core, a rotor casing, means for rotatably mounting the casing about the core, lighter than air lift means mounted about the core and in the casing, an enlargement formed on the rear 30 end of the core at the rear end of the rotor casing, said enlargement being in the form of a tail casing, lighter than air lift means in the tail casing, an induction electric motor built in between the stator core and the rotor 35 casing and propelling means on the rotor casing.

12. An air craft of the class described including, in combination, a stator core, a rotor casing, means for rotatably mounting the casing about the core, lighter than air lift means mounted about the core and in the casing, an enlargement formed on the rear 40 end of the core at the rear end of the rotor casing, said enlargement being in the form of a tail casing, lighter than air lift means in the tail casing, an induction electric motor built in between the stator core and the rotor casing and propelling means on the rotor casing, said propelling means being in the 45 form of a spiral propelling fin disposed throughout the length of the rotor casing.

13. An air craft of the class described including, in combination, a stator core, a rotor casing, means for rotatably mounting the 50 casing about the core, lighter than air lift

means mounted about the core and in the casing, an enlargement formed on the rear end of the core at the rear end of the rotor casing, said enlargement being in the form of a tail casing, lighter than air lift means 70 in the tail casing, an induction electric motor built in between the stator core and the rotor casing and propelling means on the rotor casing, said propelling means being in the form of a spiral propelling fin disposed 75 throughout the length of the rotor casing, said fin being formed in sections, said sections being hingedly mounted on the rotor casing, and means for swinging the sections to upright and down position.

80 14. An air craft of the class described including, in combination, a stator core, a rotor casing, means for rotatably mounting the casing about the core, lighter than air lift means mounted about the core and in 85 the casing, an enlargement formed on the rear end of the core at the rear end of the rotor casing, said enlargement being in the form of a tail casing, lighter than air lift means in the tail casing, an induction electric motor built in between the stator core and the rotor casing and propelling means on the rotor casing, said propelling means being in the form of a spiral propelling fin 90 disposed throughout the length of the rotor casing, said last means including arcuate racks fixed to the sections and electric motors mounted on the rotor casing and having pinions on their armature shafts meshing 95 with the arcuate racks.

100 15. An air craft of the class described, including, in combination, a stator core, a plurality of annuli on the stator core, a rotor casing disposed about the core and having interior wheel-like trestle-works rotatable 105 about the annuli, lighter than air lift means mounted about the core and in the casing, means for rotating the casing, and propeller means on the casing.

110 16. An air craft of the class described, including, in combination, a stator core, a plurality of arched stress-distributing elements on the exterior of the core alternately arranged with a plurality of interior arched stress-distributing elements, annuli mounted 115 about the stator core, wheel-like trestle-works mounted within the rotor casing, anti-friction means disposed between the trestle-works and the annuli, said annuli being disposed between the exterior stress-distributing elements, lighter than air lift means mounted about the core and in the casing for rotating the casing, and propeller means on the casing.

120 17. An air craft of the class described, including, in combination, a stator core, a plurality of arched stress-distributing elements on the exterior of the core stress-distributing elements, annuli mounted about the stator core, wheel-like trestle-works mounted with- 125

in the rotor casing, anti-friction means disposed between the trestle-works and the annuli, said annuli being disposed between the exterior stress-distributing elements, 5 lighter than air lift means mounted about the core and in the casing for rotating the casing, and propeller means on the casing,

an enlargement formed on the rear end of the core forming a tail casing, lighter than air lift means in the tail casing, elevating 10 and steering apparatus on the tail casing.

In testimony whereof I affix my signature:

JOSÉ S. CANDRAY.
